UNITED STATES PATENT OFFICE.

ALBERT E. LAMBERT, OF ALBANY, NEW YORK.

UNION GARMENT.

1,195,595.

Specification of Letters Patent. Patented Aug. 22, 1916.

Application filed October 18, 1914. Serial No. 867,013.

To all whom it may concern:

Be it known that I, ALBERT E. LAMBERT, a citizen of the United States, residing at Albany, in the county of Albany and State of New York, have invented a new and useful Union Garment; and I do hereby declare the following to be a full, clear, and exact description of the invention, such as will enable others skilled in the art to which it 5 appertains to make and use the same.

This invention relates to undergarments, and more particularly to union suits comprising integral body and leg portions.

One of the objects of the invention is to 15 provide a garment of the character mentioned, capable of expeditious and convenient donning, and constructed to afford increased wearing comfort to the user.

A further object is to provide an improved union undergarment, the manufacture 20 of which is facilitated, and the cost of which is reduced.

Other objects and advantages will be in 25 part noted hereinafter in connection with a description of the accompanying drawing, wherein is illustrated a typical embodiment of the invention.

The invention accordingly consists in the 30 features of construction, combinations of elements and arrangement of parts which will be exemplified in the construction hereinafter set forth, and the scope of the application of which will be indicated in the following claims.

In the drawing, Figures 1, 2, and 3 are 35 perspective views of a union suit, taken from different angles.

The garment illustrated comprises, in 40 general, solid knit or otherwise woven body, arm and leg portions provided with a posterior opening adjacent the crotch, and a separate posterior entrance opening communicating with the neck opening and designed for closure by overlapping flaps 45 adapted for fastening by a single button.

Referring more particularly to the drawing, the garment comprises a body 1, having the usual leg portions 2 and arms 5, of desired length. There is also provided a posterior crotch opening 3, the side flaps of 50 which over-lap for retention by a fastening 4.

The entire front of the garment is preferably of smooth, integral texture, which 55 thereby enhances the comfort and fit of the suit to the wearer. In the rear of the body

portion, the material is cut obliquely from the neck opening 6 at a point adjacent one shoulder to the waist line 9 at a point slightly beyond the vertical center of the garment, as at 12, and an insert flap 8, triangular in shape and with its acute apex 10 at the top, is sewed on two sides to the body 1 along the line of oblique severance, and also along the waist line. The third side 60 of the flap extends substantially vertically in the form shown and is left free, whereby the sides may be separated for removing the garment. An edging tape 14, preferably of one piece construction faces the neck and 65 entrance openings, and extends from the rear waist point 12 along the outer flap 13 and neck opening, at 15, and thence along the free edge of the inner flap 8, at 16, to the waist line, at 18. 75

When in use, the flap 8 lies smoothly beneath the body part constituting the outer flap 11. These parts are arranged for fastening by a single button or other device, and for this purpose, the facing 14 may be 80 provided with a buttonhole 20 adjacent the neck opening, and the flap 8 carries a registering button 21 sewed at 22. When the entrance opening is closed, the button 21 is positioned substantially above the wearer's 85 shoulder blade, thereby being readily accessible for manipulation, and, at the same time, unobtrusive.

It is to be noted that the location of the entrance opening in the back of the garment 90 is advantageous, both by reason of the resultant smoothness of the front of the garment, and also because of the increased facility thereby afforded in removing or putting on the suit, since it will be apparent 95 that in these operations the entrance opening utilizes both the neck opening and the back severance.

As many changes could be made in the above construction and many apparently 100 widely different embodiments of this invention could be made without departing from the scope thereof, it is intended that all matter contained in the above description or shown in the accompanying drawings shall 105 be interpreted as illustrative and not in a limiting sense.

Having described my invention, what I claim as new and desire to secure by Letters Patent is:

1. A union undergarment having a tubular body portion provided with separate

neck and crotch openings, and having a centrally offset entrance opening communicating with said neck opening at a point adjacent one shoulder and extending downward to the waist line, said entrance opening having inner and outer overlapping flaps, one integral with said body portion and the other comprising a triangular insert having one side sewed to said body portion 5 at the other edge of said entrance opening, and having a second side sewed to said body portion along the waist line, and a single fastening device for said entrance opening sewed to the inner flap at the neck and adjacent one shoulder.

2. A garment provided with communicating neck and entrance openings, and having inner and outer flaps below said neck

opening in the back of the garment, one of said flaps having a free edge extending 20 obliquely from said neck opening downward to the waist line, the other edges of said flap being integral with the body of the garment, and the other flap comprising a triangular piece sewed to the body along an 25 oblique edge of said entrance opening and across the waist line, and a fastening device for said flaps at said neck opening closely adjacent one shoulder.

In testimony whereof I have signed my 30 name to this specification in the presence of two subscribing witnesses.

ALBERT E. LAMBERT.
